UNITED STATES PATENT OFFICE.

THOMAS RATKOWSKI, OF CHICAGO HEIGHTS, ILLINOIS, ASSIGNOR TO AMERICAN MAN-
GANESE STEEL COMPANY, OF CHICAGO, ILLINOIS, A CORPORATION OF MAINE.

REPLACEABLE-POINT EXCAVATOR TOOTH.

Application filed July 23, 1927. Serial No. 207,854.

This invention relates to teeth for excavating implements, particularly to that class of teeth in which for the sake of prolonging the usefulness of the tooth, it is made in two parts, namely, a base suitably fashioned for mounting upon the excavating implement, for instance, a dipper, and a point replaceably mounted upon said base and usually made reversible in position upon the base in order that first one and then the other of its vertically presented faces may be introduced to the position of greater wear.

In some instances, replaceable point excavator teeth have been designed with divergent jaws on the point having rearwardly extending clamping tangs, and with a nose on the base adapted to enter between the jaws and recesses in the base extending rearwardly from the nose and adapted to receive the clamping tangs. In other instances, the point has been constructed in substantially the form of a ferrule or pocket, while the nose of the base has served as a shank to enter the pocket and to be there secured by wedges, bolts, or the like, passing through the walls of the pocket and the intervening shank. It has also been the practice to unite the jaws of the point by an integral web for the purpose of tying them together and resisting spreading under the stresses which the point meets in use, the nose being slotted to receive the tying web, and the jaws being in turn provided with overlapping lugs to embrace the members of the slotted nose to compensate for the weaknesses that would otherwise result from their bifurcation. But in prior constructions, so far as the same are known to me, there has not been cooperation between the longitudinally remote points of articulation between the base and the point of a character that successfully resists relative motion between the point and the base at such places of articulation, which is essential to the prevention of weaving or lost motion between the point and the base, and essential to the prevention of excessive stresses upon the articulating parts.

The object of the present invention is to so improve the bearing of the extreme forward end of the base in the point, as well as the construction through which the point receives said end, and the bearing of the ex-

treme rear end of the point in the base, as well as the construction of the portion of the base which establishes said bearing, in a manner to produce an improved articulation of the members at the extremes of their overlapping or meeting portions, and establish articulations which coact one with the other in a manner to render them mutually sustaining and therefore cause each to largely relieve destructive stresses that would otherwise be imposed upon the other. The object of the invention is, further, to so coordinate the construction of the meeting portions of the point and base, at places intermediate of their extreme ends, that lost motion between the parts or weaving of the point upon the base, will be still further resisted and the end portions of the articulations will be adapted to function still more effectively.

The invention proceeds upon the principle of constructing the point with not only divergent jaws from which extend rearwardly, clamping tangs of the kind heretofore used, but tying webs which integrally unite the jaws at the sides thereof instead of at an intermediate plane, and which webs converge forwardly as do the divergent jaws so that the webs and jaws together provide the four sides of a tapering pocket, and the rearwardly presented faces of the webs afford abutment surfaces through which the point is received by the base; and the base is provided not only with the known feature of upper and lower recesses which receive the clamping tangs of the point, with the longitudinal extension of the base between them, but has at the forward end of said extension a pyramidal nose, tapered vertically and laterally, which fits in the tapered pocket of the point, while the rear ends of the upper and lower recesses terminate in undercut seats for the abutment of the rear ends of the clamping tangs, and these undercut seats are specially designed, for instance, by making them of V-shaped section, to embrace the correspondingly designed rear ends of the tangs and force the latter inwardly in opposition to any spreading tendency; and, finally, the base includes in its construction cheeks integral with the forward extension of the base at the sides thereof, providing the lateral confines of the tang-receiving recesses, between which the

tangs snugly fit, and at the same time providing vertically deep stiffening webs for said extension and terminating at their forward ends in abutments substantially perpendicular to the axis of assembly which receive the rearwardly presented abutting faces of the webs on the point. The result of this combination of features is to cause the point, when drawn firmly rearward by a wedging bolt of known construction, to enter into firm rearward bearing at the end of each clamping tang and also through the vertical transverse faces of the cheeks and point webs and vertical and lateral bearing of the walls of the tapered pocket against the surfaces of the pyramidal nose, with the result that all lost motion under vertical or horizontal transverse stresses is eliminated, vertical tipping stresses are converted almost wholly into shear stresses upon the wedging bolt; and lateral stresses, by reason of the close lateral fit of the clamping tangs at the rear extremity and the fit of the nose in the pocket at the forward extremity, are taken up by the cheeks and the webs of the point.

In the accompanying drawings—

Figure 1 is a side elevation of a tooth constructed in accordance with the present invention, together with a portion of the lip 30 of a dipper in section, the rear end of the base of the tooth, which will be of ordinary construction, being omitted.

Figure 2 is a section on the line 2^x—2^x of Figure 1.

Figure 3 is a section on the line 3^x—3^x of Figure 2; and

Figure 4 is a section on the line 4^x—4^x of Figures 1 and 3.

1 represents the lip of an excavating implement, for instance, a dipper, 2 the base of a tooth mounted upon said lip, and 3 the separately formed tip or point of the tooth replaceably (and preferably, also, reversibly) mounted on said base. The point is constructed with jaws 4 having forwardly and vertically converging inner faces 4^a; webs 5 integral with said jaws at the sides thereof tying the jaws together and having their inner surfaces 5^a converging laterally in the forward direction and forming with the vertically converging jaw-surfaces 4^a a tapered ferrule or pocket 3^a (see Fig. 4); and clamping tangs 6 extending rearwardly from the jaws 4, substantially parallel with the axis of assembly and disassembly of the point, which tangs have openings 6^a to receive a clamping bolt 7 and terminate rearwardly in specially designed abutment ends 8, for instance, ends of V-shaped section.

The base 2 is constructed with upper and lower recesses 9 that receive the tangs 6, leaving a forward longitudinal extension 10 between them, which is embraced by said tangs when in assembly; a pyramidal nose 11 projecting forwardly from the extension 10 and

fitting the socket 3^a of the point; and vertically deep cheeks 12 integral with the extension 10 at the sides thereof, forming the lateral confines of the recesses 9 between which the tangs 6 snugly fit laterally, as shown in Figure 2; said cheeks terminating forwardly in abutment faces 12^a substantially perpendicular to the axis of assembly, preferably in the plane of merger between the pyramidal nose 11 and the extension 10, and receiving in longitudinal abutment the rearwardly presented faces 5^b of the webs 5. Recesses 9 terminate rearwardly in undercut seats 13 designed to conform with the abutting ends 8 of the tangs 6 and serving the function of sustaining the rear ends of the tangs not only longitudinally but transversely so that they automatically assume a firm and immovable seating under longitudinal pressure of the tooth and are pressed inwardly upon the bottoms of the recesses 9 or vertically presented surfaces of the extension 10. Clamping bolt 7, as is usual, passes through a bore 14 in the base of the tooth, in the present instance through extension 10, and bears against the forward wall of the bore 14, and the rearward walls of the openings 6^a in the tangs, with the result that the tangs 6 in the undercut 13, and the socket 3^a on the pyramidal nose 11, are drawn into firm seating.

With parts constructed as above described, it will be seen that while vertical transverse stresses upon the point 3 tend to swing the point about one of the bearing ends 8 of a tang 6, as a fulcrum, such stresses are opposed by shearing resistance of the bolt 7 and by a direct bearing of a face 4^a of the socket 3^a against a vertical wedging face 11^a of the nose 11, and these last-named faces are at such large angles to the arc of tipping movement of that portion of the point, when a rear end of a tang is acting as a fulcrum, that spreading stress upon the tang other than that which is acting as a fulcrum is very slight; moreover, such spreading stress is resisted by the hold-down face 13. When lateral stresses are imposed upon the point, they are opposed somewhat by shearing resistance of the bolt 7 due to the relatively large horizontal dimension of the seating faces 8 and 13; also by the snug fit of the tangs 6 between the lateral confines 12 of the recesses 9, but mainly by the faces 11^b of the nose in bearing against the laterally converging faces 5^a of the point, at one end of the articulation in coaction with the snug-fit of the tangs, laterally, in the recesses at the other end of the articulation.

The construction herein described provides an articulation of the point with the base, which is made very firm in all transverse directions by means of bearing surfaces which are largely at the extremes of the longitudinal dimension of articulation, with the result that weaving or lost motion of the point, on the

base, and consequent excessive localizing of stresses, so destructive to ordinary point mountings, are substantially eliminated.

I claim:

- 5 1. A replaceable point excavator tooth, comprising a base and a point adapted to be assembled with and disassembled from the base substantially in the direction of the longitudinal axis of the tooth; said point
 10 being constructed with a pair of divergent jaws and with integral lateral webs uniting said jaws and forming therewith a nose-receiving pocket, and with longitudinally extending clamping tangs terminating in base-
 15 abutting ends rearwardly remote from said pocket; said base comprising upper and lower tang-receiving recesses leaving a vertically reduced longitudinal base extension between them, and terminating at their rear ends in
 20 tang-receiving undercuts having faces with which the tangs abut, inclined in the direction to press the tangs toward the bottoms of the recesses, means being provided for forcing the tangs rearwardly upon the base,
 25 checks on the base confining the tangs laterally and terminating forwardly in abutments positioned to receive the webs of the point, and a nose projecting from the base extension beyond the abutments of the cheeks
 30 and entering the pocket of the point.
2. A replaceable point excavator tooth, comprising a base and a point adapted to be assembled with the base substantially in the direction of the longitudinal axis of the tooth; the base being constructed with upper 35 and lower tang-receiving recesses, approximately parallel with said axis, leaving between them a vertically reduced longitudinally extending body portion and terminating rearwardly in V-shaped undercut tang abutments, vertically deep cheeks integral with said base extension, forming lateral confines of said recesses and terminating in forwardly presented web-receiving abutments, and a vertically and laterally wedging nose integral 40 with said longitudinal extension, projecting beyond said cheeks; and the point being constructed with a pair of jaws, tying webs integral with and uniting said jaws at the sides thereof, said jaws and webs converging forwardly in conformity with the vertical and lateral wedging of the nose, said webs on the point and web receiving abutments on the cheeks meeting continuously a distance corresponding to the vertical dimension of the 45 extension and nose in a plane substantially perpendicular to the axis of assembly, clamping tangs extending rearwardly from the jaws of the point, embracing the forward extension of the face, fitting the recesses laterally, and conforming at their inner ends to the V-shaped abutments, and means for drawing said tangs in the direction of assembly and clamping them to the base.

Signed at Chicago Heights, Ill., this 20th 65 day of July, 1927.

THOMAS RATKOWSKI.
